UNITED STATES PATENT OFFICE.

EDWIN S. CARMAN, OF CLEVELAND, OHIO, ASSIGNOR TO THE LUDLOW TYPOGRAPH COMPANY, OF CLEVELAND, OHIO, A CORPORATION OF MAINE.

CASTING MECHANISM FOR TYPOGRAPHS.

1,124,293.

Specification of Letters Patent.

Patented Jan. 12, 1915.

Application filed February 26, 1910. Serial No. 546,108.

To all whom it may concern:
Be it known that I, EDWIN S. CARMAN, a citizen of the United States, and a resident of Cleveland, county of Cuyahoga, and State of Ohio, have invented a new and useful Improvement in Casting Mechanism for Typographs, of which the following is a specification, the principle of the invention being herein explained and the best mode 10 in which I have contemplated applying that principle, so as to distinguish it from other inventions.

The present invention relating as indicated to casting mechanism for typographs, 15 is more particularly designed for use in connection with a typograph of the general class found disclosed in United States Patent No. 856,581 to Washington I. Ludlow, June 11, 1907. It will be understood, however, that such mechanism, both in its entirety and as to various sub-combination of the parts, may be found susceptible of use in divers other connections as well. In such "Ludlow" typograph a plurality of 25 matrix bars are employed, said bars being longitudinally arranged in a trough and normally freely movable over a casting slot in such trough, so that by suitably composing or collecting said bars so as to bring 30 over said slot any desired series of characters, a matrix for a type line of the width of a column of printed matter is formed.

The object of the present invention is the taking of an impression of such assembled 35 type line by casting a slug of suitable type metal with one face in contact therewith. Aside from the means directly involved in the casting of the slug, or type line, said invention comprehends means for trimming 40 the bottom and sides of such slug to a standard size, and the transfer of the same from the casting slot wherein it is formed to a suitable galley.

To the accomplishment of the foregoing 45 objects, said invention, then, consists of the means hereinafter fully described and particularly pointed out in the claims.

The annexed drawings and the following 50 description set forth in detail certain mechanism embodying the invention, such disclosed means constituting, however, but one of various mechanical forms in which the principle of the invention may be used.

In said annexed drawings:—Figure 1 is 55 a plan view of my improved casting mecha-

nism, the bed plate which surmounts the same and receives the matrix bars being substantially entirely broken away, so as to disclose the mechanism beneath; Fig. 2 is a similar plan view of a portion of such casting mechanism, showing the casting pot, which forms a feature of such mechanism, in a different operative position; Fig. 3 is a side elevational view of such casting pot viewed from the left in Fig. 1 but in position the same as shown in Fig. 2; Fig. 4 is a part front elevation and part vertical section of the mechanism as a whole, the parts being shown in the same operative positions as in Fig. 1; Fig. 5 is a similar front elevation and section with the casting pot moved into the position shown in Figs. 2 and 3 and certain other parts differently positioned; Fig. 6 is a transverse vertical section of the machine taken on the line 6—6, Fig. 1; Fig. 6^a is a vertical section of a detail taken at right angles to the section of Fig. 6; Fig. 7 is a similar sectional view showing the plunger for forcing the molten metal from the pot into the mold in its operative position; Fig. 8 is a transverse vertical section taken on the line 8—8, Fig. 4, and on a larger scale than the preceding figures; Fig. 9 is a longitudinal, vertical section on the same larger scale, but taken on the line 9—9, Fig. 8; Fig. 10 is a longitudinal vertical section of a portion of the machine taken on the plane indicated by the line 10—10, Fig. 8; Fig. 11 is a transverse section corresponding with Fig. 8, but taken on the line 11—11, Fig. 4; Fig. 12 is a broken plan view of a portion of the mechanism showing the parts involved in a different operative position than that shown in Fig. 1 and on a larger scale; Figs. 13 and 14 are sectional views of a portion of the machine taken on planes represented by lines 13—14 and 14—14, Fig. 12, respectively; Figs. 15 and 16 are respectively an end elevation and axial section of a clutch device employed in connection with the machine; Fig. 17 is a plan view on a larger scale than in either Figs. 1 or 12, of the carriage or slide for the side trimming device; Figs. 18 and 19 are respectively a plan view 105 and a side elevation of the slug casting mold; Fig. 20 is a plan view of the "squirt" plate carried by the spout of the casting pot; Fig. 21 is a section through such spout the slug casting mold and a set of matrix bars 110

assembled over the latter in proper position for casting slug; Fig. 22 is a longitudinal section of the side-trimmer knife; Fig. 23 is an end elevation of the carriage or slide 5 shown in plan in Fig. 17; and Fig. 24 is a detail of the casting pot.

As has already been indicated, the matrix bars a^* (Fig. 21), by means of which the matrix for the type line or slug that the 10 present machine is designed to cast, is formed, are supported on a bed plate, or top A, as such part may be more properly termed with reference to the casting mechanism. The latter is alone of present interest, and hence no detailed showing of 15 the matrix bars other than in such Fig. 21, has been deemed necessary. It will be understood that the top A is movably secured to the frame A' proper of the machine, being 20 preferably hinged thereto along its rear edge, so that it can be turned back, along with the parts supported thereon, and thus disclose the casting mechanism substantially as it is shown in Fig. 1.

25 The casting mechanism proper comprises a casting pot B for providing the necessary molten metal, a mold C and carrier therefor, a knife D for trimming the bottom of the slug, another knife E for trimming the sides 30 of the slug, and means including a carry-out lever F for removing the slug from the mold and transferring the same to a suitable galley G, or other receptacle. Inasmuch as certain of these parts are more or 35 less closely related in their mounting and manner of operation, it will not be possible in the following description, to observe a sharp line of division between the same. Moreover, all of the foregoing devices and 40 means are operated from a common cam shaft H that extends longitudinally of the machine frame A', being suitably journaled in the latter in bearings a provided for this purpose at each end. The means for operating such cam shaft form an accessory detail, description of which will be reserved 45 until the last.

The general form of the casting pot B is best revealed in Figs. 2, 3 and 5, which 50 respectively afford a plan view, a side elevation, and a front elevation thereof. Such pot comprises an inner chamber B' Figs. 6 and 7, adapted to contain the molten metal, such chamber being of general cylindrical 55 form and including a sub-chamber b adapted to receive a piston or plunger b' . From such sub-chamber leads the spout b^2 through which the molten metal is forced into the mold C in the actual operation of casting. 60 Communication between the chamber B' and the sub-chamber b holding the plunger is furnished by a series of apertures b^3 in the walls of such latter chamber, which apertures are closed as the plunger 65 descends. Substantially entirely surrounding

the inner chamber and preferably cast integrally therewith, are the walls of pot B proper which thus provide an outer heating chamber. The latter has an extension b^4 that laterally surrounds the spout b^2 just 70 described as leading from the inner chamber, while an inlet opening b^5 into such outer chamber provides for the introduction of a gas burner or the heated gases therefrom for maintaining the inner chamber B' 75 of the pot at the proper temperature. Such inner chamber is provided with a removable cover b^6 through which the connecting rod b^7 for the plunger extends upwardly to its point of connection with a transverse lever b^8 80 that is pivoted to the body of the pot. In order to swing lever b^8 , and thereby reciprocate the plunger b' , an actuating rod b^9 is connected with the outer end of said lever, which rod passes substantially centrally 85 through a universal joint b^{10} that provides the support for the pot itself. Rod b^9 is hinged at the point where it thus passes through such joint so as not to interfere with the freedom of movement of the pot 90 about the joint, and is normally drawn downwardly by a tension spring b^{11} , the lower end of which is secured to an extension a' of the frame, while the upper end is attached to a yoke b^{12} forming the lower 95 end of the rod b^9 . Into such yoke extends the rear end of a lever arm b^{13} carried by a rock shaft B² ranged longitudinally of the machine frame, or, in other words, parallel with cam shaft H. At its farther end this 100 rock shaft is provided with an oppositely directed lever b^{14} arm, the outer, offset end of which engages with a cam disk H' mounted on said cam shaft. The contour of 105 said cam disk clearly appears in Fig. 6, being such as to normally retain the plunger actuating rod b^9 in raised position against the tension of spring b^{11} , so that said spring is effective only when the notch or depression h in the disk is brought into engagement with the end of the lever. Not only is 110 a quick movement of the plunger thus secured, but it will be observed that the pressure exerted upon the molten metal that is forced into the mold through the spout of 115 the casting pot, is thus forced by the resilient action of the spring and not by any positively operated part. The degree of pressure, moreover, is readily adjusted by 120 rotating the collars b^{15} to which the ends of the spring are rotatably secured, and which in turn have threaded connection with projection a' and yoke b^{12} . The casting pot B, which is thus seen to be supported upon universal joint b^{10} , is designed to be moved 125 about such support so as to periodically bring the outer end of the casting spout b^2 into register with the under side of the mold C when the latter is supported in its normal position, illustrated in Figs. 4, 6 and 7. 130

Such movement involves the shifting of the spout into alignment with said mold, raising the same thereagainst, then lowering said spout, and shifting the same aside.

5 These several movements are accomplished through the agency of a drum H^2 carried by cam shaft H , the outer surface of which drum is of varying radius and bears a groove h' differently located axially of the 10 cam shaft in different parts of said drum.

The casting pot is connected with said drum by means of a pin b^{16} slidably fitted at its upper end in an arm b^{17} projecting from the front wall of the pot. The lower end 15 of said pin passes through, and is threaded in, another arm b^{19} that is pivoted to the pot about a horizontal axis and bears at its outer end upon the curved surface of the drum. Said arm b^{19} is capable of limited

20 vertical movement against the pressure of a spring b^{18} interposed between it and arm b^{17} , while such lower end of the pin engages the groove h' in the drum, so that as the drum rotates, not only will the casting pot

25 be swung horizontally through an arc corresponding to the lateral displacement of the groove on the drum's face but also tilted up and down to correspond with the difference in radius between the different 50 parts of said drum's surface. Such groove and surface are conformed to produce the desired lateral shifting and up-and-down movement of the spout of the pot, as will be readily understood. Owing to the resilient

30 manner in which the arm b^{19} , that responds to the radial inequalities of the drum is secured to the pot, such spout may be pressed tightly against the under side of the mold, without binding, any excess pressure of the 40 drum being taken up by the spring b^{18} . The discharge end of the spout carries a "squirt" plate b^{20} as it is called, which directly contacts with the mold. Such squirt plate has a finished surface for the purpose 45 of making the joint with the mold metal-tight and is provided with a series of apertures b^{21} through which the metal is forced into the mold. (See Figs. 6, 7, 20 and 21.)

The mold C (shown in detail in Figs. 18 50 and 19) is mounted on the upper face of a vertical slide C' held between guides a^2 provided for this purpose in an intermediate portion A^2 of the machine frame (Figs. 4, 10 and 11). Such mold comprises two 55 parts adapted to form the respective lateral faces of the slug between which two parts are held two blocks c^2 that are adapted to form the end faces of such slug, said parts being held together by means of two set 60 screws c^5 . It will be readily understood how that by interposing blocks c^2 of different dimensions the mold opening c^4 may be varied to correspond with type of any desired point; while for each different width 65 of column a separate mold is supplied with

a mold opening or slot of corresponding length in ems. Mold part c' is secured to vertical slide C' by means of counter-sunk screws c^5 and dowel pins c^6 .

In vertical slide C' upon which the mold 70 is mounted there is, in turn, mounted another slide D' carrying a knife D which is disposed to move across the lower face of the mold when said slide is advanced and to trim off any projections that may extend 75 from the slug below such mold (Figs. 4, 5 and 10). Movement is imparted to the vertical or main slide C' to alternately raise and retain the mold in the position illustrated in Fig. 4 and lower the same in the 80 position illustrated in Figs. 10 and 11 by means of a cam H^3 shown in section in such Fig. 10, such cam engaging a roller c^7 that is mounted on a block c^8 adjustably secured to one face of the slide. By means of the 85 adjustable connection of the block with the slide, the positioning of the mold may be accurately predetermined. Incidentally to such vertical reciprocatory movement of the main slide, the slide D' bearing the bottom- 90 trimmer knife is advanced and retracted by means of a bell crank D^2 of the particular form clearly appearing in the figures just referred to, such crank being oscillated by companion cam H^4 mounted laterally adjacent to aforesaid main-slide actuating cam H^3 . It will be understood that the movement of the knife-bearing slide is induced partly by the direct oscillation of said bell 95 crank D^2 , and partly by the travel of the 100 roller d on the outer end of the slide in the slot d' which provides means for connection between the slide and bell crank.

In horizontal ways a^3 provided therefor near the upper portion of the machine 105 frame, such ways extending transversely of said frame, is yet another slide E' shown in detail in Fig. 17, and in each of its two operative positions in Figs. 6 and 11, respectively. In the first of said two last-named 110 figures, in which the slide appears in section, it is shown in its outer position, wherein its one end is disposed adjacently to the receiving end of the galley G that is relatively stationarily mounted on a shelf in the 115 machine frame and extends parallel with one side of such frame. In the other figure (viz. Fig. 11) such slide is shown in side elevation and in its inner position, overlying the mold C , which, as has been previously 120 described, is carried by the main, vertically reciprocable, slide C' . Said slide, moreover, may be entirely removed if desired, and constitutes but one of a set respectively provided with trim knives of the kind described 125 below, but of different dimensions for different sizes of slugs. Movement of transverse slide E' is secured from the cam shaft H by means of a cam H^5 mounted thereon and adapted to oscillate a bell crank, E^2 , the 130

upper end of which is directly pivotally connected with the under side of said slide. The actuating cams for the two slides C' and E' are so formed and timed as to bring said slides into the relationship just described and then to restore said transverse slide to the first described position (viz. that of Fig. 6) before the upward movement of the vertical slide is begun preparatory to restoring the mold to its normal operative position for the next casting operation. Said transverse slide E' is in effect a rectangular, more or less box-like structure, and bears on its under face near the inner end, a rectangular knife E, the internal dimensions of which are the standard dimensions of the slug being cast. Such knife in the second position of the slide, is brought directly into register with the upper side of the mold opening c⁴, being guided by a slotted plate e⁷ in its inner end that fits over the mold. Accordingly, when a plunger c⁹ (Figs. 10 and 11) that is carried on a supplementary slide C² secured to the front face of the main slide 25 is urged upwardly by an actuating cam H³, the slug in the mold will be pushed upwardly therefrom and through such knife, which is thus adapted to trim all four sides, or in other words, the two lateral and the two end faces of the slug to the predetermined, standard dimensions. As clearly shown in Fig. 22, the lateral blades of said trimming knife E are on a slant so as to have a shearing effect and reduce the power required to operate plunger c⁹. The construction and disposition of the supplementary slide bearing the plunger appears in Figs. 10 and 11, in both of which figures said plunger is shown in its upper, active position. This plunger, of course, requires to be withdrawn before the transverse slide is retracted. Similarly, before retraction of such transverse slide, the slug, which upon completion of the trimming operation emerges 40 through an opening e in the bottom of the slide and rests loosely against an intermediate wall e' of such slide, is transferred into a position opposite the open, receiving end of the galley G. This transfer is accomplished by means of the carry-out lever F, which has been earlier referred to and which is pivoted so as to be oscillatory in a horizontal plane substantially on a level with the bottom of the transverse slide E' (see Figs. 5 and 12). The inner end of such lever carries a hooked finger f, a compression spring f' being interposed between such end and finger, so as to tend to force the latter outwardly or toward the slug just described as 55 resting against the slide wall e'. On the bottom floor of the slide adjacent to the position thus occupied by the slug, a cam slot e² is provided in position to catch a pin f² on the under side of the finger as the lever F is 60 swung inwardly toward the central longi-

tudinal axis of the machine, thereby compressing the spring so that the finger clears the slug. However, the end of the slot being reached, the spring is allowed to force the hooked end of the finger behind the slug. 70 The lever arm upon its return movement is accordingly effective to carry the slug over into desired position for its discharge, such discharge being effected by a longitudinally reciprocable plunger F², the details of which 75 will be presently described.

The oscillation of the carry-out lever is derived from the common cam shaft H through a cam H⁷ on the outer end of the shaft that is connected to actuate a transversely reciprocable yoke f⁴. The latter in turn oscillates a vertically disposed rock shaft f⁵ upon the upper end of which said lever F is mounted. (See Figs. 13 and 14.)

The longitudinally reciprocable plunger F² for finally discharging the slugs into the galley G is operated by means of a cam h³ attached to the outer face of the main-slide actuating cam H³, (Figs. 8 and 9). Such attached cam is in the form of a triangular plate that once during each revolution of the main cam is brought against the lower end of a lever f⁶ pivoted to the inner wall of the machine frame, the upper end of which lever is directly connected to the plunger in question. A spring f⁷ serves normally to retain the plunger in its outer position, and the lower end of said lever in position to be engaged by the triangular cam plate.

Inasmuch as it is desirable, for obvious reasons, that the registration between the side-trimming knife, carried by the transverse reciprocable slide, and the opening in the mold be very accurate, I provide means for locking said transverse slide in its inner position. Such means consist in preferred form, of a vertically reciprocable dowel pin e⁸, Figs. 8 and 9, mounted in an opening in one of the ways a³ whereon said slide is carried. The latter is provided with a corresponding opening adapted to receive the end of the dowel pin and thus be secured in place. To raise the dowel pin and thus lock the slide, a lever e⁴ pivoted in ears a⁴ at one end of the machine frame is provided, such lever being pivotally connected with the lower end of the pin, and its oscillation being effected by a cam H⁸ mounted on the outer face of bottom-trimmer slide actuating cam H⁴ and a transversely disposed lever e⁵, pivoted to the side of the machine frame at its outer end and engaging such cam at its inner end.

Although certain details of construction more or less accessory in their character remain to be described, the general sequence of operations may be well set forth at this juncture. While the matrix bars are being assembled by the operator to compose a line of type such as is sectionally illustrated in 125

Fig. 31, the casting pot B occupies the inoperative position illustrated in Figs. 2 and 5, the latter of which figures likewise represents the remaining mechanism in substantially the same quiescent or inoperative state, save that the bottom trimmer slide has been urged forwardly, whereas in the state in question it would occupy the position shown in Fig. 4. Upon completion of the matrix assembling operation, the casting mechanism is then started in operation by rotating cam shaft H either directly or through a suitable power drive as will be hereinafter explained, to swing the spout of the casting pot B around into position directly beneath the mold C and thereupon raise the same into close fitting contact with the under side of said mold as shown in Fig. 4. In this position said pot is retained pending the next step in the general operation, which is to permit lever b^{14} to drop into the notch h in cam H' , thereby allowing spring b^{11} to actuate plunger b' and force sufficient molten metal up spout b^2 to completely fill the opening in the mold C. The metal thus received in the mold immediately cools sufficiently to retain its form, and constitutes the "slug" with the handling of which the succeeding operations of the machine are concerned. Preliminarily, however, the casting pot is lowered and then moved sidewise by the operation of cam drum H^2 as hereinbefore described, so as to leave entirely clear the space beneath the mold C. The trimming slide D' follows the pot as it moves sidewise so as to reach the slug as the main slide C' which carries the mold begins to lower. While such main slide is descending, the angle of the slot d' in lever D' carries the bottom trimming knife D across the lower face of the mold so as to trim off any depending portion of the slug, but such bottom-trimming slide and knife are thereupon retracted by the time the main slide finishes its descent. Transverse slide E' which carries side trimming knife E is then rapidly moved directly over the mold C now occupying its lowermost position and is locked in place by the raising of the dowel pin e^3 . The ejector plunger e^9 is moved up and ready to push the slug out of the mold as soon as slide E' is thus locked. As has been previously explained, such plunger, in ejecting the slug, at the same time forces the same through the side trimming knife E, so that when the slug finally emerges through the bottom of the slide F', it is in completely finished form, having had both its bottom and sides trimmed to standard dimensions. As soon as the ejector e^9 has completed this operation and moves down so as to clear said slide E', the latter starts back, having been unlocked in the meantime by the withdrawal of dowel pin e^3 . At the same time that the

slide E' is moved in to the operative position just described, the carry-out lever F is also swung into its inner position. Such carry-out lever remains thus until the slide moves back again. Incidentally to such movement of the slide, the cam slot e^2 thereon catches the pin f^2 on the finger f and compresses the spring f' so as to permit said finger to clear the slug until the end of the slot is reached whereupon the finger is forced behind the slug by such spring. The lever F does not itself move up to this time, or in other words, until the slide E' has been restored to its outer position, and it will be observed that it is the movement of the slide from its inner to such outer position that actuates the finger of the lever in the fashion just explained. When the slide E' is thus restored to its outer position, the lever F is swung outwardly so as to carry the slug out into alignment with the open end of the galley G. The plunger F' thereupon pushes the slug into the galley, thus finishing the cycle of operations.

In order to prevent the heat of the casting pot B from rising directly and so raising the immediately superposed portion of the top or cover A' to an uncomfortable temperature, an insulator is provided in the form of a number of horizontally extending sheet metal plates b^{22} (Figs. 1 and 3) fastened to the plunger operating lever b^3 . Said plates are secured together by shoulder pins or screws and separators, as will be readily understood, and owing to the clear space left between them for the air to circulate, all objectionable effects that might otherwise be due to the close proximity of the casting pot to the rest of the mechanism, are eliminated. Moreover, a hood B^3 and pipe b^{22} are provided for carrying off the heat from the spout of the pot when the latter occupies its inoperative position shown in Figs. 2, 3 and 5. At the same time the opening in the top A (or bed plate, as it may be termed, having regard to the composing mechanism mounted thereon) is closed by means of a transversely shiftable shutter or slide K that normally occupies a position above the plunger actuating lever as shown in Figs. 1, 6 and 7, but, upon the depression of the main slide C' with the casting mold C, is thrust forwardly through the agency of a bell crank h having slotted connection therewith at its upper end, while its lower end is operatively connected with the front face of said main slide. Another plate c^{12} , that is pivotally secured at its lower end to the face of main slide C', serves to shield the parts located therebeneath from the heat of the pot and any drippings of molten metal, (see Figs. 4 and 5). A spring normally holds the upper end of said shield in contact with the face of slide C' as shown in said figure, while still permitting it to be

6 moved out of the way by plunger c^3 , as slide C^2 is raised. Upon such movement of the slide the plunger engages the inner face of said plate c^{12} swinging the same outwardly.

5 Obviously, so far as the operation of the various foregoing parts composing the line casting mechanism are concerned, it is wholly immaterial how the main cam shaft H , which actuates such parts of the machine, is itself operated, and if desired, a hand 10 crank or any form of manual operating means may be employed. Inasmuch, however, as such operation is cyclic in character, the machine being put through its series of 15 operations after each successive line has been composed by the proper manipulation of the matrix bars carried on the top or bed plate A , I have provided an arrangement for utilizing a power drive which will free the 20 operator from all attention to the operation of the casting mechanism, save at the beginning of each line, when he needs merely to start the same. Such power drive (Figs. 4, 25 15 and 16) comprises a back shaft M with a belt pulley m to which the motor or other driving engine is connected. Back shaft M also bears a pinion m' that meshes directly with a larger gear m^2 on the corresponding 30 end of the cam shaft H . The gear m^2 , however, turns freely on said shaft so that the back shaft M may be driven continuously without effecting any operation of the casting mechanism. In order to non-rotatably 35 secure the gear m^2 to the shaft H when desired, a clutch member m^3 is, accordingly provided, such clutch member being held in a sleeve m^4 non-rotatably mounted on the shaft and being thrown into operation by a spring m^4 whenever released from a pivotal 40 cam lever or detent m^5 . The latter is normally held by a spring m^6 in position to engage said clutch member and disconnect the same from gear m^2 , but may be retracted into 45 inoperative position by a rod m^7 , which is connected with a pedal or hand-lever (not shown) as found most convenient, having regard to the other manipulations that claim the operator's attention. Accordingly, by 50 momentarily releasing said detent, it will be evident that cam shaft H will be given one complete rotation, whereupon the detent again automatically disconnects the gear m^2 from the shaft and leaves the latter at rest until again purposely started. In other 55 words, the operator throws in the clutch when he is ready to cast a slug, and as soon as the initial stage of such casting operation has been completed, he can proceed with the composing of the next line of type, leaving 60 the machine to automatically complete the trimming and discharge of the slug.

65 Other modes of applying the principle of my invention may be employed instead of the one explained, change being made as regards the mechanism herein disclosed, pro-

vided the means stated by any of the following claims or the equivalent of such stated means be employed.

I therefore particularly point out and distinctly claim as my invention:—

1. In mechanism of the class described, the combination of a substantially horizontally disposed slug casting mold; a pot for molten metal mounted below said mold and having a spout adapted to register therewith, said pot being movable about angularly related axes so as both to raise and lower such spout and to shift the same laterally with respect to said mold; and means for forcing metal from said pot into said mold. 70

2. In mechanism of the class described, the combination of a substantially horizontally disposed slug casting mold; a pot for molten metal having a spout adapted to register with said mold from below, said pot being mounted on a universal joint, whereby such spout may be independently shifted either vertically or laterally with respect to said mold; and means for forcing metal from said pot into said mold. 75

3. In mechanism of the class described, the combination of a substantially horizontally disposed slug casting mold; a pot for molten metal having a spout adapted to register with said mold from below, said pot being mounted on a universal joint, whereby such spout may be independently shifted either vertically or laterally with respect to said mold; means for moving said pot so as successively to shift such spout into alinement with said mold, raise the same thereagainst, then lower said spout, and shift the same aside; and means adapted to force the metal from said pot into said mold when the spout of the former is thus raised against the latter. 95

4. In mechanism of the class described, the combination of a substantially horizontally disposed slug casting mold; a pot for molten metal having a spout adapted to register with said mold from below, said pot being mounted on a universal joint, whereby such spout may be independently shifted either vertically or laterally with respect to said mold; a rotatable cam connected with said pot and adapted to move the same so as successively to shift such spout into alinement with said mold, raise the same thereagainst, then lower said spout, and shift the same aside; and means adapted to force the metal from said pot into said mold when the spout of the former is thus raised against the latter. 110

5. In mechanism of the class described, the combination of a substantially horizontally disposed slug casting mold; a pot for molten metal having a spout at one end adapted to register with said mold from below, said pot being pivotally supported 115

- near its other end so as to be oscillatory about both a vertical and a horizontal axis; a rotatable drum of varying radius located adjacent to such first end of said pot and bearing a guide on its curved face, such guide being differently located axially of said drum in different parts of such face; and a member on such first end of said pot engaging such guide.
6. In mechanism of the class described, the combination of a substantially horizontally disposed slug casting mold; a pot for molten metal having a spout at one end adapted to register with said mold from below, said pot being pivotally supported near its other end so as to be oscillatory about both a vertical and a horizontal axis; a rotatable drum of varying radius located adjacent to such first end of said pot and bearing a guide on its curved face, such guide being differently located axially of said drum in different parts of such face; and a member resiliently connected with such first end of said pot and engaging such guide.
7. In mechanism of the class described, the combination of a substantially horizontally disposed slug casting mold; a pot for molten metal having a spout adapted to register with said mold from below, said pot being mounted on a universal joint, whereby such spout may be shifted both vertically and laterally with respect to said mold; a rotatable drum of varying radius bearing a guide on its curved face; a member on said pot slidably engaging the guide on said drum, whereby, as the latter rotates, said pot is moved so as successively to shift such spout into alignment with said mold, raise the same thereagainst, then lower said spout, and shift the same aside; and means adapted to force the metal from said pot into said mold when the spout of the former is thus raised against the latter.
8. In mechanism of the class described, the combination of a substantially horizontally disposed slug casting mold; a pot for molten metal having a spout adapted to register with said mold from below, said pot being mounted on a universal joint, whereby such spout may be shifted both vertically and laterally with respect to said mold; a rotatable drum of varying radius bearing a groove on its curved face; a pin resiliently mounted on said pot and slidably engaging the groove on said drum, whereby as the latter rotates, said pot is moved so as successively to shift such spout into alignment with said mold, raise the same thereagainst, then lower said spout, and shift the same aside; and means adapted to force the metal from said pot into said mold when the spout of the former is thus raised against the latter.
9. In mechanism of the class described,
- the combination of a substantially horizontally disposed slug casting mold; a pot for molten metal having a spout adapted to register with said mold from below, said pot being mounted on a universal joint, whereby such spout may be shifted both vertically and laterally with respect to said mold; and means for forcing metal from said pot into said mold, said means including a plunger in said pot and an exteriorly connected member for reciprocating said plunger, said member passing substantially centrally through such universal joint.
10. In mechanism of the class described, the combination of a substantially horizontally disposed slug casting mold; a pot for molten metal having a spout adapted to register with said mold from below, said pot being mounted on a universal joint, whereby such spout may be shifted both vertically and laterally with respect to said mold; and means for forcing metal from said pot into said mold, said means including a plunger in said pot, a lever mounted on said pot and connected with said plunger, and an exteriorly connected rod for swinging said lever, said rod passing substantially centrally through such universal joint.
11. In mechanism of the class described, the combination of a substantially horizontally disposed slug casting mold; a pot for molten metal having a spout adapted to register with said mold from below, said pot being mounted on a universal joint, whereby such spout may be shifted both vertically and laterally with respect to said mold; means for forcing metal from said pot into said mold, said means including a plunger in said pot, a lever mounted on said pot and connected with said plunger, and an exteriorly connected rod for swinging said lever, said rod passing substantially centrally through such universal joint; and heat insulating means carried by said lever for preventing the heat of the pot from rising directly.
12. In mechanism of the class described, the combination of a substantially horizontally disposed slug casting mold; a pot for molten metal having a spout adapted to register with said mold from below, said pot being mounted on a universal joint, whereby such spout may be shifted both vertically and laterally with respect to said mold; means for forcing metal from said pot into said mold, said means including a plunger in said pot and an exteriorly connected member for reciprocating said plunger, said member passing substantially centrally through such universal joint; and a plurality of spaced horizontally extending metal plates secured to said lever for preventing the heat of the pot from rising directly.
13. In mechanism of the class described, the combination of a substantially horizon-

5 tally disposed slug casting mold; a pot for molten metal having a spout adapted to register with said mold from below, said pot being mounted on a universal joint, whereby such spout may be shifted both vertically and laterally with respect to said mold; means for moving said pot so as successively to shift such spout into alinement with said mold, raise the same thereagainst, 10 then lower such spout, and shift the same aside; and means for forcing metal from said pot into said mold, said means including a plunger in said pot and a member for reciprocating said plunger, said member 15 passing substantially centrally through such universal joint.

14. In mechanism of the class described, the combination of a substantially horizontally disposed slug casting mold; a pot for molten metal having a spout adapted to register with said mold from below, said pot being mounted on a universal joint, whereby such spout may be shifted both vertically and laterally with respect to said mold; a 20 rotatable cam connected with said pot and adapted to move the same so as successively to shift such spout into alinement with said mold, raise the same thereagainst, then lower such spout, and shift the same aside; 25 means for forcing metal from said pot into said mold, said means including a plunger in said pot and a member for reciprocating said plunger, said member passing substantially centrally through such universal 30 joint; and a cam moving in unison with said drum and adapted to actuate said plunger-reciprocating member.

15. In mechanism of the class described, the combination of two carriers movable 40 transversely of each other, a mold borne by one of said carriers, means for supplying molten metal to said mold, means borne by the other carrier for trimming the sides of the slug thus formed in said mold, means 45 for moving said carriers so as to bring the second over the first, and means adapted thereupon to push such slug from said mold and through said side-trimming means.

16. In mechanism of the class described, 50 the combination of a vertically reciprocable carrier, a mold borne thereby, means for supplying molten metal to said mold, a second carrier reciprocable transversely of said first carrier, means borne by said second carrier for trimming the sides of the slug formed in said mold, means for lowering said first carrier and then shifting said second carrier to position the same over the former, and means adapted thereupon to 55 push such slug from said mold and through said side-trimming means.

17. In mechanism of the class described, 60 the combination of a vertically reciprocable slide, a mold borne thereby and projecting laterally therefrom, means for supplying

molten metal to said mold, a second slide reciprocable transversely of said first slide, a knife borne by said second slide for trimming the sides of the slug formed in said mold, means for lowering said first slide and then shifting said second slide to position said side-trimming knife over said mold, and a plunger movably mounted on said first slide below said mold and adapted to push such slug from said mold upwardly through said side-trimming knife. 70 75

18. In mechanism of the class described, the combination of a vertically reciprocable slide, a mold borne thereby and projecting laterally therefrom, a movable casting pot 80 adapted to supply molten metal to said mold from below and then withdraw, a second slide reciprocable transversely of said first slide, a knife borne by said second slide for trimming the sides of the slug formed in said mold, means for lowering said first slide and then shifting said second slide to position said side-trimming knife over said mold, and a plunger movably mounted on said first slide below said mold and adapted to push such slug from said mold upwardly through said side-trimming knife. 85 90

19. In mechanism of the class described, the combination of two carriers movable transversely of each other, a mold borne by 95 one of said carriers, means for supplying molten metal to said mold, means borne by the other carrier for trimming the sides of the slug thus formed in said mold, means for moving said carriers so as to bring the second over the first, means adapted thereupon to push such slug from said mold and through said side-trimming means, and a movable member adapted to engage and remove said slug. 100 105

20. In mechanism of the class described, the combination of a vertically reciprocable carrier, a mold borne thereby, means for supplying molten metal to said mold, a second carrier reciprocable transversely of said 110 first carrier, means borne by said second carrier for trimming the sides of the slug formed in said mold, means for lowering said first carrier and then shifting said second carrier to position the same over the former, means adapted thereupon to push such slug from said mold and through said side trimming means, and a carry-out lever adapted to engage and remove said slug. 115

21. In mechanism of the class described, 120 the combination of a vertically reciprocable slide, a mold borne thereby and projecting laterally therefrom, means for supplying molten metal to said mold, a second slide reciprocable transversely of said first slide, a knife borne by said second slide for trimming the sides of the slug formed in said mold, means for lowering said first slide and then shifting said second slide to position said side-trimming knife over said mold, a 125 130

plunger movably mounted on said first slide below said mold and adapted to push such slug from said mold upwardly through said side-trimming knife, a relatively stationary galley adjacent to the path of travel of said second slide, and a carry-out lever adapted to engage and move such slug into alignment with said galley.

22. In mechanism of the class described, the combination of a vertically reciprocable slide, a mold borne thereby and projecting laterally therefrom, a movable casting pot adapted to supply molten metal to said mold from below and then withdraw, a second slide reciprocable transversely of said first slide, a knife borne by said second slide for trimming the sides of the slug formed in said mold, means for lowering said first slide and then shifting said second slide to position said side-trimming knife over said mold, a plunger movably mounted on said first slide below said mold and adapted to push a slug from said mold upwardly through said side-trimming knife, a relatively stationary galley adjacent to the path of travel of said second slide, a carry-out lever adapted to engage and move such slug into alignment with said galley, and a plunger for discharging such slug so therein.

23. In mechanism of the class described, the combination of two carriers movable transversely of each other, a mold borne by one of said carriers, means for supplying molten metal to said mold, means for trimming the bottom of the slug thus formed while still in said mold, means borne by the other carrier for trimming the sides of such slug, means for moving said carriers so as to bring the second over the first, and means adapted thereupon to push such slug from said mold and through said side-trimming means.

24. In mechanism of the class described, the combination of a vertically reciprocable carrier, a mold borne thereby, means for supplying molten metal to said mold, means movably mounted on said carrier for trimming the bottom of the slug thus formed while still in said mold, a second carrier movable transversely of said first carrier, means borne by said second carrier for trimming the sides of such slug, means adapted to lower said first carrier and incidentally actuate the bottom trimming means mounted thereon, means adapted to shift said second carrier to position the same over the first carrier, and means adapted thereupon to push such slug from said mold and through said side-trimming means.

25. In mechanism of the class described, the combination of a vertically reciprocable slide, a mold borne thereby and projecting laterally therefrom, means for supplying molten metal to said mold, a knife mov-

ably mounted on said slide and adapted to trim the bottom of the slug thus formed while still in said mold, a second slide reciprocable transversely of said first slide, a knife borne by said second slide for trimming the sides of such slug, means adapted to lower said first slide and incidentally actuate said bottom-trimming knife, means adapted to shift said second slide to position said side-trimming knife over said mold, and a plunger movably mounted on said first slide below said mold and adapted to push such slug from said mold upwardly through said side-trimming knife.

26. In mechanism of the class described, the combination of a suitably supported matrix; a carrier, said matrix and carrier being relatively movable, the one away from and toward the other; a mold borne by said carrier; means for supplying molten metal to said mold; a device for trimming the bottom of the slug thus formed while still in said mold; a second carrier movable transversely of the direction of relative movement between said matrix and first carrier; a device borne by said second carrier for trimming the sides of such slug upon the latter being ejected from said mold; and means adapted to eject such slug.

27. In mechanism of the class described, the combination of a suitably supported matrix; a carrier, said matrix and carrier being relatively movable, the one away from and toward the other; a mold borne by said carrier; means for supplying molten metal to said mold; a device for trimming the bottom of the slug thus formed while still in said mold; a second carrier movable transversely of the direction of relative movement between said matrix and first carrier; a device borne by said second carrier for trimming the sides of such slug upon the latter being ejected from said mold; and means adapted successively to separate said matrix and first carrier, actuate said bottom-trimming device, move said second carrier to position said side-trimming device between said mold and matrix, and thereupon eject such slug.

28. In mechanism of the class described, the combination of movably supported matrix-bearing members; a carrier movable toward and away from said members; a mold borne thereby; means for supplying molten metal to said mold; a device for trimming the bottom of the slug thus formed while still in said mold; a second carrier movable transversely of the direction of movement of said first carrier; a device borne by said second carrier for trimming the sides of such slug upon the latter being ejected from said mold; and means adapted to eject such slug.

29. In mechanism of the class described, the combination of movably supported matrix-bearing members; a carrier movable to-

ward and away from said members; a mold borne thereby; means for supplying molten metal to said mold; a device for trimming the bottom of the slug thus formed while still in said mold; a second carrier movable transversely of the direction of movement of said first carrier; a device borne by said second carrier for trimming the sides of such slug upon the latter being ejected from said mold; and means adapted successively to actuate said first carrier to withdraw said mold from said members, actuate said bottom-trimming device, move said second carrier to position said side-trimming device between said mold and members, and thereupon eject such slug.

30. In mechanism of the class described, the combination of a slug casting mold; a movable support therefor; a knife for trimming a slug cast in said mold, said knife being reciprocably mounted on said support; and an independently mounted lever oscillatory in the direction of movement of said knife and connected to thus reciprocate the same.

31. In mechanism of the class described, the combination of a slug casting mold; a movable support therefor; a knife for trimming a slug cast in said mold, said knife being reciprocably mounted on said support; and an independently mounted lever oscillatory in the direction of movement of said knife, said lever having a curved way connecting the same with said knife, whereby both oscillation of said lever and movement of said support are effective to reciprocate said knife.

32. In mechanism of the class described, the combination of a substantially horizontally disposed slug casting mold; a vertically movable support therefor; a knife reciprocably mounted on said support and adapted to trim the bottom of a slug cast in said mold; and an independently mounted lever oscillatory in the direction of movement of said knife and connected to thus reciprocate the same.

33. In mechanism of the class described, the combination of a substantially horizontally disposed slug casting mold; a vertically movable support therefor; a knife reciprocably mounted on said support and adapted to trim the bottom of a slug cast in said mold; and an independently mounted lever oscillatory in the direction of movement of said knife; said lever having a curved way connecting the same with said knife, whereby both oscillation of said lever and movement of said support are effective to reciprocate said knife.

34. In mechanism of the class described, the combination of a substantially horizontally disposed slug casting mold; a vertically movable support therefor; a slide reciprocably mounted on said support and provided

with a knife adapted to trim the bottom of a slug in said mold; a cam shaft alined with the direction of movement of said slide and provided with a cam for moving said mold support; a lever oscillatory in the same direction and connected to reciprocate said slide; and a second cam on said shaft for oscillating said lever.

35. In mechanism of the class described, the combination of a substantially horizontally disposed slug casting mold; a vertically movable support therefor; a slide reciprocably mounted on said support and provided with a knife adapted to trim the bottom of a slug in said mold; a cam shaft alined with the direction of movement of said slide and provided with a cam for moving said mold support; a lever oscillatory in the same direction and connected to reciprocate said slide; and a second cam on said shaft for oscillating said lever, the latter having a curved way connecting the same with said slide, whereby both oscillation of the lever and the movement of said support are effective to reciprocate said knife.

36. In mechanism of the class described, the combination of a reciprocable slide; a knife on said slide adapted to trim the sides of a slug pushed therethrough; a relatively stationary galley adjacent to the path of travel of said slide; and a carry-out lever adapted to engage a slug upon the latter emerging through said knife and to transfer the same into alinement with said galley.

37. In mechanism of the class described, the combination of a reciprocable slide; a knife on said slide adapted to trim the sides of a slug pushed therethrough; a relatively stationary galley adjacent to the path of travel of said slide; and a carry-out lever adapted to engage a slug upon the latter emerging through said knife and to transfer the same into alinement with said galley, engagement of said lever with such slug being controlled by movement of said slide.

38. In mechanism of the class described, the combination of a reciprocable slide; a knife on said slide adapted to trim the sides of a slug pushed therethrough; a relatively stationary galley adjacent to the path of travel of said slide; a carry-out lever provided with a resilient slug-engaging member; and a cam element on said slide adapted to control the operation of such member, said lever being adapted to transfer a slug engaged by the latter into alinement with said galley.

39. In mechanism of the class described, the combination of a substantially horizontally reciprocable slide formed with an aperture; a knife on the under side of said slide alined with such aperture and adapted to trim the sides of a slug pushed therethrough; a relatively stationary galley adjacent to the path of travel of said slide; and a carry-out

lever movable in the same plane as said slide and adapted to engage a slug upon the latter emerging through such knife and aperture in the slide and to transfer such slug into alinement with said galley.

40. In mechanism of the class described, the combination of a substantially horizontally reciprocable slide formed with an aperture; a knife on the under side of said slide alined with such aperture and adapted to trim the sides of a slug pushed therethrough; a relatively stationary galley adjacent to the path of travel of said slide; and a carry-out lever movable in the same plane as said slide, said lever being adapted to engage a slug upon the latter emerging through such knife and aperture and to transfer the same into alinement with said galley, engagement of said lever with said 15 slug being controlled by movement of said slide.

41. In mechanism of the class described, the combination of a substantially horizontally reciprocable slide formed with an aperture; a knife on the under side of said slide alined with such aperture and adapted to trim the sides of a slug pushed therethrough; a relatively stationary galley adjacent to the path of travel of said slide; 20 a carry-out lever movable in the same plane as said slide and provided with a resilient slug-engaging member; and a cam element on said slide adapted to control the operation of such member, said lever being adapted 25 to transfer a slug engaged by the latter into alinement with said galley.

42. In mechanism of the class described, the combination of a reciprocable slide; a knife on said slide adapted to trim the sides 40 of a slug pushed therethrough; a relatively stationary galley adjacent to the path of travel of said slide; a carry-out lever adapted to engage a slug upon the latter emerging through said knife and to transfer the same 45 into alinement with said galley; and a plunger for discharging such slug into said galley.

43. In a machine of the class described, the combination of a slug casting mold; 50 matrix-bearing members adapted to be supported against one end of said mold; means respectively adapted to supply molten metal to the other end of said mold, trim the corresponding end of the slug while still in the 55 mold, separate said mold and matrix-bearing members, and eject such slug through such first mold-end; and a side-trimming device shiftable into operative position with respect to such first mold-end, so as to receive 60 such slug when thus ejected.

44. In a machine of the class described, the combination of a slug casting mold; 55 matrix-bearing members adapted to be sup-

ported against one end of said mold; means respectively adapted to supply molten metal 65 to the other end of said mold, trim the corresponding end of the slug while still in the mold, separate said mold and matrix-bearing members, and eject such slug through such first mold-end; a side-trim- 70 ming device shiftable into operative position with respect to such first mold-end, so as to receive such slug when thus ejected; and means for removing such slug from said device. 75

45. In a machine of the class described, the combination of a substantially horizontally disposed slug casting mold; matrix-bearing members adapted to be supported above said mold; means respectively adapt- 80 ed to supply molten metal to said mold from below, trim the bottom of the slug while still in the mold, lower the latter, and push such slug upwardly therethrough; and a side-trimming device shiftable into position 85 over said mold so as to receive such slug when thus pushed upwardly.

46. In a machine of the class described, the combination of a substantially horizontally disposed slug casting mold; matrix- 90 bearing members adapted to be supported above said mold; means respectively adapt- ed to supply molten metal to said mold from below, trim the bottom of the slug while still in the mold, lower the latter, and push 95 such slug upwardly therethrough; a side- trimming device shiftable into position over said mold so as to receive such slug when thus pushed upwardly; and means for removing such slug from such device. 100

47. In a machine of the class described, the combination of matrix-bearing members; a movable slug casting mold adapted in one position to press one face against said members; means coöperative with the other face 105 of said mold to cast a slug therein; and a shutter adapted to be interposed between said mold and members, when said mold is moved away from said matrix-bearing members.

48. In a machine of the class described, the combination of substantially horizontally disposed matrix-bearing members; a vertically movable slug casting mold disposed below said members and adapted to press one face thereagainst; means coöperative 110 with said mold from below to cast a slug therein; and a shutter adapted to be inter- posed between said mold and members, when said mold is moved away from said matrix-bearing members. 115

Signed by me this 24th day of February, 1910.
